UNITED STATES PATENT OFFICE

WALTER D. SHAFFER, OF CHICAGO, ILLINOIS, ASSIGNOR TO UNITED SHOE MACHINERY CORPORATION, OF PATERSON, NEW JERSEY, A CORPORATION OF NEW JERSEY

METHOD OF AND APPARATUS FOR MAKING SHOES

Application filed November 15, 1928. Serial No. 319,590.

This invention relates to the manufacture of shoes and more particularly to methods of and apparatus for operating on the marginal portions of leather outsoles attached to shoes. 5 The invention is herein exemplified in relation to a welt shoe.

In women's shoes thin-edged soles are desired to give a light, dainty appearance. Certain conditions encountered in welt shoes 10 make the production of a thin edge especially difficult. For example, the welt makes the edge of the outsole appear to be thicker than it really is, and the magnitude of the problem of producing thin edges is correspondingly 15 great for that reason. Again, the outsole stitches in a welt shoe necessarily lie in the marginal extension of the sole and so close to the finished edge thereof that they restrict the range of operation in any attempt to reduce 20 the thickness of the margin by cutting away some of the stock thereof.

Shoemaking requirements do not permit the removal of any portion of the tread surface of the outsole, since the grain side of the 25 leather is always placed at the bottom and its integrity must be preserved to provide for a uniform bottom finish. Consequently, it is not permissible to produce a thin edge by beveling the grain surface of an outsole. 30 Moreover, welt shoes of the grade or type in which thin-edged soles are especially desired are commonly provided with outsoles formed with stitch-receiving channels and with channel flaps to cover the stitches and to preserve 35 the grain surface in its entirety for bottom-finishing. Thus, the preservation of a channel flap is an additional reason why the grain surface of an outsole may not be beveled to produce a thin edge.

40 It has been proposed heretofore to produce a thin-edged outsole for a welt shoe by beveling the margin thereof from the root of the channel flap to the edge of the margin before stitching the outsole to the welt, but such procedure deprives the stitch-receiving portion 45 of the outsole of some of its strength and establishes the location of the bevel independently of the location of the outsole stitches.

In view of the conditions above described, 50 an object of the present invention is to pro-

vide an improved method of making welt shoes according to which the margins of channeled outsoles may be advantageously reduced after the soles have been stitched to the welts. As herein shown this method may be practiced by separating the welt from the margin of the outsole outside the line of stitches connecting them, trimming the margin of the outsole to reduce its thickness while the welt is separated therefrom and, preferably, bracing the margin of the outsole against the trimming cutter while maintaining the separation specified. This method not only guards against cutting into the welt 55 but provides for a firmer backing of the margin of the outsole than one in which the welt itself is utilized. Consequently, uniform thinning of the margin may be obtained, since the trimming is not affected by variations in the thickness of the welt, or by welts 60 of different thickness or different degrees of softness. In the practice of the above-described method, a separating element interposed between the welt and outsole may be utilized to guard against cutting the outsole 65 stitches and to lead the trimming cut along a course parallel to the line of the stitches. Preferably, and as herein shown, the sole-reducing cut bevels the tread side of the margin 70 of the sole to form a feather edge at the flesh 75 side of the sole and reduces the width of the trimmed margin so that the feather edge thus produced will lie inside the edge of the welt and be covered by the channel flap when the flap is laid. Moreover, for reasons that will 80 appear later, the invention provides for concaving the beveled margin of the sole. 85

Another object of the invention is to provide improved apparatus for trimming the margin of the sole of a welt shoe, by the 90 aid of which the procedure above described may be practiced. To this end a feature of the invention consists in a trimming machine comprising a trimming cutter formed and arranged to reduce the margin of an outsole 95 that is stitched to the welt of a shoe, and a thin shield formed and arranged to project between the welt and the margin of the sole and thereby to prevent the trimming cut from reaching the stitches. The shield may 100

thus be used to guide the shoe so that the trimming cut will run parallel to the line of the outsole stitches and to brace the margin of the outsole against the cutter while 5 maintaining the welt out of contact with the cutter. Preferably, and as illustrated, provision is also made for maintaining the channel flap out of contact with the cutter.

Another result much desired in women's 10 shoes is closed welt or rand creases in the shank portions. The shank portion of a last is undercut along both the inner side and the outer side, but more so along the inner side, this condition being due to a marked trans- 15 verse convexity of the last. Therefore, to obtain a closed crease, it is necessary to conform the outsole to the transverse convexity of the last. To some extent the leveling operation, to which a shoe is commonly sub- 20 jected after the outsole has been stitched, imparts a transverse curvature to the outsole, but the degree of curvature required to close the creases along the shank is so great that the outsole springs back more or less toward 25 its original shape when the leveling pressure is removed, with the result that the creases do not remain closed. In some shoe factories the leveling operation is supplemented by 30 blows of a hammer to close the creases along the shank, but even this expedient does not cause the creases to remain closed. The conditions adverse to closed creases are worse in 35 welt shoes because the welt and the margins of the soles are connected by a bond of adhesive applied prior to the sole-laying operation, and the bond of adhesive prevents relative creeping of the welt and the margins of the outsole when the levelling pressure is applied. Thus, while both the welt and the 40 margins of the outsole may be flexed by the leveling pressure their inability to creep relatively one to the other supplements their tendency to remain flat and causes reopening of the creases as soon as, or shortly after, the 45 leveling pressure is removed.

In view of the conditions last described, another object of the invention is to provide an improved method of making welt shoes according to which the outsoles may be conformed more closely than heretofore to the transverse convexity of the lasts in the shank portions, to the end that the welt crease may be closed tightly and retained in that relation. In accordance with this object the 50 invention provides a novel method which consists in rupturing the bond of adhesive between the margin of the welt and the margin of the outsole, conforming both of these margins to the transverse convexity of the 55 last and thereby causing relative creeping of the margins relatively one to the other, and reestablishing adhesion between the margins in their changed relation brought about by their relative creeping incidental to closing the welt crease, as by a sole leveling op-

eration. In some cases the adhesive substance applied to one or both of the confronting faces of the welt and the outsole prior to the sole-laying operation may be sufficiently sticky when the leveling operation is performed to cause subsequent adhesion of the two margins after the leveling operation, but if not, a fresh coat of adhesive may be applied to these surfaces before the leveling pressure is applied.

It has been stated herein that the invention provides for concaving the margin of the outsole to produce a thin edge. A concave cut is desirable not only to insure the safety of the outsole stitches but also to provide sharply defined shoulders on the trimmed margins to receive the leveling pressure and to transmit that pressure to the welt along the line of the outsole stitches, to the end that the welt will be pressed firmly against the upper adjacent to the inseam. Such shoulders, lying as they do adjacent to the outsole stitches, are instrumental also in causing the described creeping of the welt and the margins of the outsole when the sole is leveled.

Referring to the accompanying drawings, Fig. 1 is a cross-sectional view of the shank portion of a welt shoe provided with a channeled outsole, and includes a portion of a tool in the act of separating the welt from the margin of the outsole;

Fig. 2 is a similar view of the same shoe at a later stage, showing the result of beveling one margin of the outsole in accordance with this invention;

Fig. 3 is a sectional view of the same shoe at a still later stage, showing the result of beveling both margins of the outsole and closing the welt crease as by a leveling operation;

Figs. 4 and 5, the scale magnitude of which is twice that of Figs. 1, 2 and 3, are sectional views corresponding to the upper portions of Figs. 2 and 3, respectively; Fig. 4 showing the condition of the shoe prepared for the leveling operation while Fig. 5 shows the results of the leveling operation substantially as shown in Fig. 3;

Fig. 6 is a cross-sectional view of the shank portion of a channeled outsole of the type shown in the other figures, the dotted lines representing the sole margins before being trimmed;

Fig. 7 is a vertical section of an improved trimming machine comprising certain novel features by which it is adapted to bevel the margins of an outsole with the result shown in Figs. 2 and 6;

Fig. 8, the scale magnitude of which is twice that of Fig. 7, is a duplicate of the elements shown in the lower left part of Fig. 7; and

Fig. 9 is a front elevation of a shield shown also in Fig. 7.

The method hereinafter described of trim-

ming the margins of an outsole to produce thin edges may be practiced not only at the shank portions of welt shoes but also around the foreparts, although present styles require 5 very thin edges at the shanks only. The invention will, therefore, be described more especially with regard to thinning the edges at the shanks, but it is to be understood that the appended claims directed to this part 10 of the invention are not to be construed as limited to any locality unless so limited in terms or by their context.

For the purpose of describing the present invention, it is to be understood that the 15 usual or any well-known procedure for making a welt shoe may be followed up to and including the step of stitching a channeled outsole to the welt of a shoe. Fig. 1 illustrates a welt shoe of well-known construction, the 20 manufacture of which has progressed to that stage at which the outsole is stitched to the welt. The elements are as follows: a last 10, an upper 12 which may or may not include the usual lining (not illustrated), a channeled insole 14, a welt 16, stitches 18 forming the inseam by which the upper and the welt are connected to the insole, a channeled leather outsole 20 having a channel flap 22 and a margin 24, outsole stitches 26 forming 25 the outseam by which the margin of the outsole is connected to the welt adjacent to the inseam, and a steel shank stiffener 28. It is to be observed that the welt 16 and the outsole margin 24 as shown at the bottom of 30 Fig. 1 form, conjointly, a thick edge which would be still thicker if the channel flap 22 were laid against it without reducing said margin.

According to common practice in the 35 manufacture of welt shoes the flesh surfaces of outsoles are coated with an adhesive prior to the sole-laying operation, one purpose of the adhesive being to maintain the outsole in the desired relation to the shoe until the 40 outsole is connected to the welt by the stitches 26. The adhesive thus applied extends to the edges of the outsole and results in a bond between the margin 24 and the welt 16. The adhesion of the welt to the margin of the 45 outsole is insured by cooperative feeding members of a rough-rounding and channeling machine by which those elements of the shoe are clamped with considerable pressure soon after the adhesive has been applied and 50 before it has set. Consequently, when the outsole stitching operation has been performed, the welt and the margin 24 adhere 55 one to the other so strongly that it is not possible for them to creep relatively one to the 60 other.

In view of the conditions above described, the first step of my improved method, as 65 herein exemplified, consists in rupturing the bond of adhesion between the welt and the margin 24. This step may be performed by

the use of any suitable instrumentality such, for example, as a wedge-shaped tool represented at 30 in Fig. 1. A tool of the type shown may be inserted manually between the welt and the margin 24 and drawn along the 70 outseam, or, if desired, a power-operated machine provided with a wedge-shaped tool may be used. For example, in a machine for performing this operation, the tool 30 may be vibrated edgewise while the shoe is held in the 75 hands of the operator with the thin extremity of the tool between the elements to be separated.

Having separated the welt from the outsole margin 24 wherever it is desired to reduce the thickness of said margin, the margin 24 is next beveled to a thin edge so that the thin edge will be at the top or flesh side of the sole, none of the grain surface of the sole being removed. In many cases it is desirable to reduce the width in addition to beveling the margin 24 (see Fig. 6) so that when the channel flap 22 is subsequently closed upon the beveled margin and thereafter trimmed, together with the welt, by an edge-trimming operation, it will completely cover and conceal the margin as shown in Figs. 3, 5 and 6. In Fig. 6, the margins of the outsole prior to this beveling operation are indicated by dotted lines, while the beveled surfaces are indicated at 32. In performing this beveling operation it is preferable, for reasons hereinafter described, to concave the beveled surface as illustrated in Figs. 2, 4 and 6. Moreover, it is desirable to 90 reduce the margin 24 without removing any stock from the welt 16. Accordingly, the invention provides for maintaining the welt 95 out of contact with the margin of the outsole while the beveling operation is being performed. These results may be obtained by the use of the beveling apparatus illustrated in Figs. 7 and 8 to be hereinafter described.

Having beveled the margin 24 of the outsole wherever a thin edge is desired, the 110 flesh side of the channel flap 22, the beveled surfaces 32, and the flesh side of the welt 16 may be coated with fresh adhesive, the channel flap may be laid to close the channel as represented in Fig. 4, and the shoe may then 115 be subjected to a sole-leveling operation. This operation need not differ from the sole-leveling operations heretofore practiced, but, certain improved results are obtained from such an operation in consequence of rupturing the initial bond of adhesion between the 120 welt and the margin 24 and in consequence of concaving the beveled surface 32 of the margin.

Commercial sole-leveling machines now 125 commonly used are provided with rolls that travel back and forth on the tread surface of the outsole while the last on which the shoe is held is supported by a jack. A suitable leveling machine is illustrated, for example, in 130

United States Letters Patent No. 1,004,155, granted September 26, 1911, on application of Andrew Eppler. A heavy pressure is applied to the leveling roll while the jack is rocked to distribute the leveling pressure over the entire area of the shank and forepart of the shoe. This operation conforms the outsole and insole to the curvatures of the bottom of the last, and presses the channel flap 22 against the beveled margin 24 and against the outer margin of the welt 16.

As a result of trimming the margin 24 with a concave bevel, as hereinbefore explained, a sharply defined shoulder or edge 34 is formed on the margin. Thus, when the leveling pressure is applied to the shoulder as indicated, for example, by an arrow in Fig. 4, it is concentrated upon that portion of the welt through which the outseam stitches 26 extend and cause, by their tension, a gaping crease between the welt and the upper. One effect of the concentration of pressure at this point is to close this crease as shown in Figs. 3 and 5. Since the welt and the margin of the outsole are not adhesively connected at this stage they may readily creep relatively one to the other in consequence of being conformed by the leveling pressure to the transverse curvature of the last, thus facilitating the closing of the crease. At the same time, the leveling pressure is sufficient to transform the sharply defined shoulder 34 into a convex formation as shown in Fig. 5 with the result that the channel flap, the beveled margin 24 and the welt are closely compacted. The fresh adhesive applied to the channel flap, the beveled margin 24 and the welt immediately prior to the leveling operation maintains these elements in their compacted relation as shown in Fig. 5 after the leveling pressure is removed, and the changed relation of the welt and the outsole due to their relative creeping is also maintained by the adhesive. The finishing operations commonly performed subsequently to the leveling operation may be performed as heretofore.

In beveling the margins 24 it is, of course, of primary importance to avoid cutting into the outsole stitches 26. At the same time it is desirable to maintain the beveling cut close to the stitches, particularly along the shank of the shoe where the marginal sole extension should be relatively narrow. To this end, and to facilitate beveling the margin as above explained, the present invention provides an improved trimming machine illustrated in Figs. 7, 8 and 9. The frame and general organization of the illustrated trimming machine are similar to the construction shown, for example, in United States Letters Patent No. 1,235,709, granted August 7, 1917, on application of C. K. MacDonald.

In the illustrated trimming machine, a power-driven cutter shaft 36 is journaled in

horizontal bearings one of which is a bushing 38 affixed in a frame 40. The forward end of the shaft 36 is provided with a frusto-conical extension 42 that carries an expandable split sleeve 44 of well-known construction. A toothed trimming cutter 46 is mounted on the sleeve 44 and is secured thereto by a screw 48 and a washer 50, the shaft extension 42 being bored and tapped to receive the screw. The cutting teeth of the cutter 46 are arranged to trim or bevel the bottom of the margin 24 of the outsole, and they have a convex profile 52 to impart to the trimmed margin 24 the concave bevel 32 hereinbefore described.

A stationary shield 54, arranged in front of the cutter, is reduced to a thin edge at its lower end to act as a wedging element and is formed and arranged to project between the sole margin 24 and the welt 16, thereby bending the welt away from the sole margin so that it may run on the outsole stitches 26. When the shield is suitably adjusted according to the size and style of a given cutter it not only prevents the cutter from attacking the outsole stitches but also guides the course of trimming by the crease between the welt and the sole margin and maintains the bevel 32 at a uniform distance from the stitches. In addition, the shield by projecting between the sole margin 24 and the welt, prevents the cutter from attacking the welt, and at the same time it braces the margin against the cutter. The shield 54 is adjustably affixed to a stationary bracket 56 by a clamping screw 58, a slot 60 being formed in the shield to provide for vertical adjustment thereof according to the radial dimension of the cutter. An abutment 62 is secured to the bracket 56 by a clamping screw 64, said abutment being horizontally adjustable by reason of having a slot 66 through which the screw extends. The abutment is arranged to engage the upper end of the shield 54 to supplement the holding effect of the clamping screw 58 against upward pressure against the shield. The abutting surfaces of the shield and the abutment 62 are beveled to form a miter joint 68 whereby their adjustments may be coordinated to maintain the lower end of the shield at the desired level. Provision is also made for adjusting the shield 54 in lines parallel to the axis of the cutter, as may be required to regulate the cut. For this purpose the bracket is provided with a slot 70 to receive a clamping bolt 72 screwed into the frame 40. Preferably the seat formed on the frame for the bracket 56 is grooved to prevent angular movement of the bracket without depending entirely upon the clamping effect of the bolt. Dotted lines 74 in Fig. 7 represent one of two parallel shoulders formed on the frame 40 to constrain the bracket against angular movement.

The illustrated construction also provides for maintaining the channel flap 22 out of contact with the cutter. For this purpose an annular, bell-mouthed back-guard 76 (Fig. 7) is arranged behind but in contiguous relation to the cutter. This back-guard is preferably mounted so that it will not partake of the rotation of the cutter, but at the same time be capable of turning in consequence of frictional drag of the channel flap. Accordingly, the back-guard is rotatably mounted on a stationary sleeve 78 that surrounds the cutter shaft and has telescopic connection with the bushing 38. A set-screw 80 having threaded connection with the supporting sleeve 78 is arranged to engage the bushing 38 to maintain the sleeve in the desired position of adjustment, the sleeve being axially adjustable to place the back-guard close to the cutter without quite touching it. An annular flange 82 at the forward end of the sleeve (Fig. 8) supports the back-guard in concentric relation to the cutter, while a shoulder 84 extending radially from said flange provides an abutment to maintain the back-guard in contiguous relation to the cutter. The rim of the back-guard projects slightly beyond the teeth of the cutter to bend the channel flap away from the cutter and guide it so that it will clear the cutter.

When using the trimming means above described, the operator may hold the shoe in his hands and feed it past the cutter in substantially the same manner as that followed in the use of edge-trimming machines. It is customary to grasp the body of the shoe in the left hand and to place the fingers of the right hand against the tread face of the outsole. This causes the fore finger of the right hand to lie adjacent to the upper edge of the sole. Accordingly, the right fore finger may conveniently be placed in the angle formed by the tread face of the outsole and the channel flap 22, that finger thus being effective to press the channel flap against the rim of the back-guard which will have rolling contact therewith and turn relatively to the supporting sleeve 78.

The bell-mouth formation of the back-guard 76 provides an annular chamber 86 to receive dust and chips from the cutter, and the back-guard is preferably provided with a series of holes 88 to discharge the dust and chips. Moreover, the supporting sleeve 78 is also preferably provided with a series of holes 90 to discharge whatever dust or chips enter it from the chamber circumscribed by the back-guard.

Having thus described my invention, what I claim as new and desire to secure by Letters Patent of the United States is:

1. That improvement in methods of making welt shoes which consists in separating the welt and the margin of the stitched outsole of a shoe outside the line of the outsole

stitches, and trimming said margin of the outsole while the welt is separated therefrom.

2. That improvement in methods of making welt shoes which consists in separating the welt and the margin of the stitched outsole of a shoe outside the line of the outsole stitches, trimming said margin of the outsole while the welt is separated therefrom, and bracing said margin while it is being trimmed and while the welt is separated therefrom. 76

3. That improvement in methods of making welt shoes which consists in separating the welt and the margin of the stitched outsole of a shoe outside the line of the outsole stitches, and beveling said margin of the outsole while the welt is separated therefrom. 80

4. That improvement in methods of making welt shoes which consists in separating the welt and the margin of the stitched outsole of a shoe outside the line of the outsole stitches, beveling said margin of the outsole while the welt is separated therefrom, and bracing said margin while it is being beveled. 85

5. That improvement in methods of making welt shoes which consists in separating the welt and the margin of the stitched outsole of a shoe outside the line of the outsole stitches, and trimming said margin of the outsole to form a feather edge at the flesh side of the outsole while the welt is separated therefrom. 90

6. That improvement in methods of making welt shoes which consists in separating the welt and the margin of the stitched outsole of a shoe outside the line of the outsole stitches, trimming said margin of the outsole to form a feather edge at the flesh side of the outsole while the welt is separated therefrom, and bracing said margin while it is being trimmed as specified. 105

7. That improvement in methods of making welt shoes which consists in separating the welt and the margin of the stitched outsole of a shoe outside the line of the outsole stitches, beveling the margin of the outsole with a concave cut to form a feather edge at the flesh side of the outsole while the welt is separated therefrom, and bracing said margin while it is being beveled as specified. 110

8. That improvement in methods of making welt shoes which consists in separating the welt and the margin of the stitched outsole of a shoe outside the line of the outsole stitches, trimming said margin of the outsole, and guiding the course of such trimming by the crease between the welt and said margin. 120

9. That improvement in methods of making welt shoes which consists in separating the welt and the margin of the stitched outsole of a shoe outside the line of the outsole stitches, trimming said margin of the outsole, and guiding the course of such trimming by 125

- the outsole stitches between the welt and said margin.
10. That improvement in methods of making welt shoes which consists in wedging 5 apart the welt and the stitched outsole of a shoe outside the line of the outsole stitches, and trimming said margin of the outsole while and where a wedging element is between said margin and the welt.
11. That improvement in methods of making welt shoes which consists in interposing a thin metal shield between the welt and the margin of the stitched outsole of a shoe outside the line of the outsole stitches, trimming said margin of the outsole while the 15 welt is separated therefrom by such shield, removing the shield, and closing the crease between the welt and the trimmed margin.
12. That improvement in methods of making welt shoes which consists in separating the welt and the margin of the stitched outsole of a welt shoe, reducing the thickness and the width simultaneously of said margin by trimming the latter without trimming the 20 welt, and maintaining separation of the welt and said margin while and where such trimming takes place.
13. That improvement in methods of making welt shoes which consists in separating 30 the welt and the margin of the stitched outsole of a welt shoe, beveling the bottom side of said margin, and simultaneously bracing the welt side of said margin and maintaining the welt out of contact therewith at the locality where the beveling is performed.
14. That improvement in methods of making welt shoes which consists in separating the welt and the margin of the stitched outsole of a welt shoe, beveling the bottom side 40 of said margin, and controlling the depth of such beveling by the crease between the welt and said margin.
15. That improvement in methods of making welt shoes which consists in separating the welt and the margin of the stitched outsole 45 of a welt shoe as far in as the stitches that connect them, trimming one side of said margin with a beveling cut, and controlling the location of such cut by said stitches.
16. That improvement in methods of making welt shoes which consists in separating the welt and the margin of the stitched outsole of a welt shoe as far in as the stitches that connect them, trimming said margin while 55 maintaining the welt out of contact therewith at the trimming locality, and controlling the course of such trimming by said stitches.
17. That improvement in methods of making 60 welt shoes which consists in separating the welt and the margin of the stitched outsole of a welt shoe as far in as the stitches that connect them, trimming the edge and one face of said margin simultaneously to reduce the thickness and the width thereof, and
- controlling the course of such trimming by said stitches.
18. That improvement in methods of making welt shoes which consists in separating the welt and the margin of the stitched outsole 70 of a welt shoe as far in as the stitches that connect them, reducing the thickness and the width of said margin with a concave cut that forms a feather edge at the welt side of said margin, and controlling the progress of such cut by said stitches between the welt and said margin.
19. A trimming machine comprising a trimming cutter formed and arranged to reduce the width of the margin of a channeled outsole stitched to a welt shoe, and a non-driven shield formed and arranged to project between the welt and said margin and to run on the stitches connecting them and thereby prevent the trimming cut from reaching 80 said stitches.
20. A trimming machine comprising cutting means formed and arranged to reduce the thickness and the width of the margin of a channeled outsole stitched to a welt shoe, and a shield formed and arranged to run between the welt and said margin to brace the latter against said cutting means and to control the course of the trimming cut.
21. A trimming machine comprising cutting means formed and arranged to trim the bottom of the margin of a channeled outsole stitched to a welt shoe, and a shield arranged to project between the welt and said margin to separate them and to brace said margin 90 against the cutting means.
22. A trimming machine comprising a trimming cutter formed and arranged to trim the margin of an outsole attached to a welt shoe, and a stationary member formed and arranged to run between the welt and said margin to control the course of the trimming cut.
23. A trimming machine comprising a trimming cutter having a convex profile 100 formed and arranged to cut a concave bevel on the margin of an outsole stitched to a welt shoe, and means arranged to guide the shoe so that said cutter will trim close to but not into the outsole stitches.
24. A trimming machine comprising cutting means formed and arranged to bevel the bottom side of the margin of an outsole stitched to a welt shoe and thereby form a feather edge at the welt side of the margin, and means arranged to maintain separation of the welt and said margin adjacent to the cutting locality and to brace said margin 110 against said cutting means.
25. A trimming machine comprising a trimming cutter having a convex profile 115 formed and arranged to reduce the width of the margin of a channeled outsole attached to a welt shoe by beveling said margin and forming a feather edge at the welt side there-

- of, and means arranged to run between the welt and said margin to brace the latter against said cutter and to prevent the cutter from attacking the welt.
26. A trimming machine comprising a trimming cutter formed and arranged to trim the margin of a channeled outsole attached to a welt shoe, means arranged to run between the welt and said margin to brace the latter against the cutter and to separate the welt from the cutter, and means arranged to guide the channel-flap so that it will clear said cutter. 5 70
27. A trimming machine comprising a trimming cutter formed and arranged to trim the margin of a channeled outsole attached to a shoe, means for operating said cutter, means arranged in front of the cutter to brace said margin against the cutter, and means arranged behind the cutter to bend the channel-flap away from said cutter. 15 75
28. A trimming machine comprising a trimming cutter formed and arranged to trim the margin of a channeled outsole attached to a shoe, means for operating said cutter, an annular guard arranged to maintain the channel-flap out of contact with said cutter, and non-rotary means by which said guard is supported so that it may be turned by the frictional effect of the work thereon. 25 80
29. A trimming machine comprising a rotary trimming cutter formed and arranged to trim the margin of a channeled outsole attached to a shoe, means for driving said cutter, an annular back-guard contiguous to said cutter and arranged to fend the channel-flap from said cutter, and a stationary sleeve by which said back-guard is supported. 35 85
30. A trimming machine comprising a rotary trimming cutter formed and arranged to trim the margin of a channeled outsole attached to a shoe, means for driving said cutter, a bell-mouthed back-guard arranged to fend the channel-flap from said cutter and formed to provide a chamber to receive dust and chips from said cutter, said back-guard having one or more outlets for the discharge of dust and chips. 40 90
31. That improvement in methods of making welt shoes which consists in rupturing a bond of adhesive connecting the welt and the margin of the stitched outsole of a shoe on a last, and conforming the welt and the outsole to the transverse convexity of the last and thereby causing relative creeping of the welt and said margin to a relation other than the one in which they were formerly held by said bond of adhesive. 45 95
32. That improvement in methods of making welt shoes which consists in rupturing a bond of adhesive connecting the welt and the margin of the stitched outsole of a shoe on a last, and leveling the sole and thereby causing relative creeping of said margin and the welt to avoid tensioning said margin. 50 100
33. That improvement in methods of making welt shoes which consists in rupturing a bond of adhesive connecting the welt and the margin of the stitched outsole of a shoe on a last, bending said margin and the welt toward the last and thereby causing relative creeping of said margin and the welt. 55 105
34. That improvement in methods of making welt shoes which consists in rupturing a bond of adhesive connecting the welt and the margin of the stitched outsole of a shoe on a last, and thereafter closing the welt-crease and simultaneously causing relative creeping of the welt and said margin by leveling the outsole. 60 110
35. That improvement in methods of making welt shoes which consists in rupturing a bond of adhesive connecting the welt and the margin of the stitched outsole of a shoe in which the outsole has a channel flap for covering the stitches, trimming said margin while said flap is open, coating the trimmed margin with an adhesive, closing said flap, leveling the outsole and thereby causing relative creeping of the welt and said margin to avoid tensioning the latter. 65 115
36. That improvement in methods of making welt shoes which consists in joining by an adhesive the welt and the margin of a channeled outsole of a shoe, raising a channel flap of the outsole to open the channel, stitching the outsole to the welt adjacent to the inseam, rupturing the bond of adhesive between the outsole and the welt outside the outseam, beveling the margin of the outsole with a concave cut to form a thin edge at the top and a sharply defined shoulder at the bottom of said margin, closing the channel flap, leveling the outsole and thereby transforming said shoulder to a convex formation, closing the welt-crease and causing relative creeping of the welt and said margin of the outsole by the leveling pressure. 70 120
37. That improvement in methods of making welt shoes which consists in rupturing a bond of adhesive connecting a shank portion of the welt and the margin of the stitched outsole of a shoe on a last, and reestablishing adhesion of the welt and said margin at said shank portion by bending the margin toward the body of the shoe with pressure sufficient to close the welt-crease and to cause relative creeping of the welt and said margin. 75 125
- In testimony whereof I have signed my name to this specification. 120
- WALTER D. SHAFFER. 130
